(57) **CLAIM**

The ornamental design for a bottle as shown and described.

DESCRIPTION

FIG. 1 is a front/side perspective view of a bottle showing my design.

FIG. 2 is a bottom/front/side perspective view of the bottle of FIG. 1.

FIG. 3 is a back/side perspective view of the bottle of FIG. 1.

FIG. 4 is a front view of the bottle of FIG. 1.

FIG. 5 is a back view of the bottle of FIG. 1.

FIG. 6 is a first side view of the bottle of FIG. 1.

FIG. 7 is a second side view of the bottle of FIG. 1.

FIG. 8 is a top view of the bottle of FIG. 1; and,

FIG. 9 is a bottom view of the bottle of FIG. 1.

The broken lines in the figures represent portions of the bottle that form no part of the claimed design.

1 Claim, 8 Drawing Sheets
